UNITED STATES PATENT OFFICE.

LEO C. SMITH, OF MINNEAPOLIS, MINNESOTA, ASSIGNOR TO SMITH SYSTEM HEATING CO., OF MINNEAPOLIS, MINNESOTA, A CORPORATION OF MINNESOTA.

HEATING AND VENTILATING SYSTEM.

1,138,805.

Specification of Letters Patent.

Patented May 11, 1915.

Application filed February 23, 1911. Serial No. 610,214.

To all whom it may concern:

Be it known that I, LEO C. SMITH, a citizen of the United States, residing at Minneapolis, in the county of Hennepin and State 5 of Minnesota, have invented certain new and useful Improvements in Heating and Ventilating Systems; and I do hereby declare the following to be a full, clear, and exact description of the invention such as will enable others skilled in the art to which it 10 appertains to make and use the same.

My invention relates to heating and ventilating systems wherein a stove or heater is placed within a surrounding jacket through 15 which the air of the room is circulated.

The invention is directed particularly to the provision of improved means for drawing the foul air from the room, to a greater or less extent, as desired, and, to such ends, 20 the invention consists of the novel devices and combinations of devices hereinafter described and defined in the claim.

In the accompanying drawings, which 25 illustrate the invention, like characters indicate like parts throughout the several views.

Referring to the drawings, Figure 1 is a view partly in vertical section and partly in side elevation, illustrating my invention applied to a heater of the general character 30 above indicated; and Fig. 2 is a detail view in rear elevation, showing the foul air pipe and the damper provided therein.

The heater 1, which may be of any suitable construction, is placed within a surrounding jacket 2, which may also be of any suitable construction but which is arranged so that the air of the room may be circulated therethrough. Hence, as shown, the said jacket 2 is open both at its upper and lower 40 ends and its lower end is spaced above the floor. The smoke pipe from the heater 1 is indicated by the numeral 3.

The foul air pipe 4 is extended vertically through the jacket 2 and one wall thereof is 45 either formed as part of or directly secured to the outer surface of the heater 1, so that a large amount of heat will be conducted into the walls of the said foul air pipe and radiated therefrom, thus producing a strong 50 draft in the said foul air pipe. The lower end of the foul air pipe 4 should be extended considerably below the lower end of the jacket 2, so that it will pick up the relatively heavy foul air at a point close to the floor. 55 The upper end of the foul air pipe 4 may be

extended to any suitable point of discharge, either through the roof or otherwise, to the exterior of the building, but should be independent of the smoke pipe 3 and of the chimney or flue into which the said smoke 60 pipe is connected. At a point preferably just above the upper edge of the jacket 2, the foul air pipe 4 is shown as provided with a rectangular damper box or compartment 5 provided, as shown, at its rear with a discharge passage 6 having, preferably, the same cross section or conducting capacity as the body of the foul air pipe.

Located within the compartment 5 and hinged thereto at its upper edge, by a small 70 shaft 7, is a damper 8. This damper 8, when moved into a vertical position indicated by dotted lines in Fig. 1, will entirely close the discharge passage 6, so that all of the foul air passed upward through the pipe 75 4 will be discharged from the room. When this damper 8 is set in the intermediate position shown by full lines in Fig. 1, part of the foul air will pass back into the room through the passage 6, while part thereof 80 will pass upward through the foul air pipe 4 and will be discharged from the room. When the valve 8 is turned upward into a horizontal position, it will close the upper portion of the foul air pipe 4 and will cause 85 all of the air circulated in the pipe 4 to pass back into the room. This arrangement of the damper is highly important and is thought to be novel. It provides for a large 90 range of variation in the amount of foul air that will be drawn from the room and, at the same time, permits the said foul air pipe, and the surface of the heater with which the foul air pipe is in contact, to be always in use to its full capacity for the circulation of air therethrough and the radiation of heat.

As already indicated, the air circulated through the foul air pipe 4 may be partly or wholly returned to the room. Hence, when the device is not used for drawing foul 100 air from the room, it may be used as an auxiliary device, acting in conjunction with the jacket 2, to circulate the air of the room. If the provision for circulating the air of the room through the foul air pipe was not made, it is evident that whenever the damper was moved to prevent the discharge of foul air, the foul air pipe would become a dead air space and its total cross section 105 would be deducted from the air space con- 110

tained between the heater and jacket. As shown, the damper 8 is adapted to be adjusted by an arm 9 secured to one end of the shaft 7, and having frictional engagement with the side of the damper box 5. In my improved device above described, that portion of the foul air pipe 4, which is below the damper 8, is always in full action, either to discharge all of the air circulated there-through out of the room, or to discharge all of the air circulated therethrough back into the room, or to discharge part of the air out of the room and part of the air back into the room. Furthermore, the circulation of air through the said foul air pipe does not in any way affect the draft of the stove or heater.

What I claim is:

The combination with a heater having a surrounding jacket through which the air of

the room is circulated, of a foul air pipe, extended vertically through said jacket and provided at its intermediate portion with an expanded compartment, said compartment having a lateral discharge passage opening directly into the room, and a damper mounted in said compartment, said damper being adjustable, in one extreme position to close said lateral discharge passage, in another extreme position to close the upper portion of said foul air pipe, and, in an intermediate position, to open more or less of both said lateral discharge passage and the upper portion of said foul air pipe.

In testimony whereof I affix my signature in presence of two witnesses.

LEO C. SMITH.
